UNITED STATES PATENT OFFICE.

CHARLES L. BASTIAN, OF CHICAGO, ILLINOIS, AND RALPH L. FARNHAM, OF GRAND HAVEN, MICHIGAN, ASSIGNORS TO THE BASTIAN-BLESSING COMPANY, OF CHICAGO, ILLINOIS, A CORPORATION OF ILLINOIS.

TEMPERATURE CONTROL.

Application filed January 21, 1925. Serial No. 3,827.

This invention relates to a novel and improved temperature control for use in places where there are a plurality of compartments which it is desired to maintain at different temperatures as for example in soda fountain equipment. In such equipment it is customary to provide one compartment for the storage of ice cream packers and one or more adjoining compartments for the cooling of water and other liquids used with the fountain. The temperature of the compartment in which the ice cream is stored must be maintained below freezing, for example, at 6° or 8° F., whereas the compartments or compartment for cooling the liquids must not go below 32° F. and it is preferably maintained at a minimum of approximately 34° F. Various means have been devised in the past for maintaining the difference in temperatures, but most of them have involved use of a separate cooling means for each compartment.

It is a primary object of our invention to provide a device wherein a plurality of compartments may be cooled by use of the same medium, provision being made for passage of the medium from one chamber to another and this passage being controlled automatically to keep the medium in the different compartments at the required temperature.

A still further object of our invention is to provide a device of the above character which will permit circulation of the cooling medium from one compartment to another when necessary to maintain the desired temperatures, but which will maintain perfect insulation between the compartments when circulation therebetween is not taking place.

A still further object of our invention is to provide a novel and improved control for the operation of the necessary valves in our system and which shall include means which may be employed when the device is out of use as in shipment, without endangering it because of excessive pressure caused by expansion of the medium used with the controlling device.

In the accompanying drawings in which

we have shown a selected embodiment of our invention:

Fig. 1 is a rear view of a portion of a soda fountain, parts being broken away.

Fig. 2 is a section on the line 2—2 of Fig. 1.

Referring now to the drawings, our invention is illustrated as being embodied in a fountain comprising a plurality of compartments 1, 2 and 3. The compartment 1 is used as a cooling compartment through which are passed coolers 4 to cool the liquids used with the fountain. This compartment contains a cooling medium such as brine which will maintain the liquid at a temperature slightly above freezing, say 34° F.

The compartment 2 is adapted to contain ice cream packers and these packers are kept cool by means of a cooling medium such as brine in the compartment surrounding the packers. The contents of the packers must be kept at a much lower temperature than the liquids used with the fountain and therefore it is necessary to keep the brine at a temperature ranging from zero to 10° F.

Hitherto the brine or other cooling medium in the two compartments has been kept separate and various means have been devised for keeping them at their desired temperatures. However, we contemplate using the same cooling medium for both compartments and for that purpose we provide the insulated wall 5 which separates the compartments 1 and 2 with a plurality of openings 6 and 7. These openings are preferably placed one above the other and we have shown two such openings in this embodiment.

In each of these openings is placed a suitable valve and as they are substantially identical in construction, we shall limit our description to the one which is placed in the opening 6. By reference to Fig. 1, it will be seen that this valve comprises a fibre sleeve 8 inserted in the opening 6 and provided with an annular shoulder 9 forming a valve seat at one end thereof. The sleeve is held in place by a lock nut 10 co-operating with the shoulder 9, both the shoulder and lock nut being separated from

the wall by rubber washers 11 and 12. By this construction it will be seen that there is no metal extending from one compartment to another and that there are no metal parts 5 in contact so as to form conducting means for heat from one compartment to another.

Mounted on fulcrums 13 and 14 on the wall 5 are levers 15 and 16 connected with the valve stems 17 and 18. Each of these 10 stems is provided with a fibre check 19 and 20 respectively adapted to engage and be seated in the shoulder 9 of the respective sleeve 8 to close the valve. The ends of the levers 15 and 16 are operatively connected 15 to the longitudinally expansible corrugated member 21 which is a commercial article known by the trade name "sylphon", so as to operate in unison to open or close the valves. The levers are urged against the 20 sylphon by a suitable spring 22. The sylphon is connected with a sylphon tank 23 which together with the sylphon is filled with a suitable liquid such as alcohol, which expands and contracts enough on a variation of 5° F. to move the ends of the levers 15 and 16 approximately one-eighth of an inch. The arms of the levers are so arranged that a movement of one-eighth of an inch at one end will open the valve at 25 the other end of each lever one-quarter of an inch, although this arrangement may be varied as desired. The action of the sylphon 21 for the levers 15 and 16 may be controlled by any suitable means such as a turnbuckle 24 having right and left hand threads and pressed against the wall 25 of the compartment 1 and against the neck 26 of the 30 sylphon tank.

To avoid dangerous pressure in the sylphon 40 tank when the apparatus is being shipped or when not in use for any other reason, we provide the neck 26 with a comparatively large auxiliary sylphon 27 which may be adjusted as desired by a screw 28, the sylphon and screw being supported in a suitable framework 29. The action of the sylphon is controlled by a spring which normally forces the sylphon against a stop inside thereof. When the pressure becomes 45 abnormal, the action of the spring is overcome and the sylphon is forced outwardly until it comes in contact with the screw 28.

In operation and assuming that both 55 valves are closed, they will remain closed until the temperature of the cooling medium in the compartment 1 rises to a point where it will cause the alcohol or other fluid in the sylphon to expand, thus operating the levers 15 and 16 and opening the valves. 60 Circulation of the brine between the compartments 1 and 2 will then take place, the cooler medium passing from the compartment 2 to the compartment 1 through the lower valve and the warmer medium passing 65 from the compartment 1 to the com-

partment 2 through the upper valve. It is understood that the medium in the compartment 2 is cooled to the desired temperature by any suitable means, such means being well known and forming no part of our invention. While we have shown two valves, we do not intend to be limited thereby, as our invention is capable of use with either one or more valves. The turnbuckle 24 may be operated to adjust the sylphon 21 and 70 thereby regulate the amount by which the valves are opened. As the medium in the compartment 1 becomes cooled by the circulation of cooler fluid from the compartment 2 the sylphon 21 will contract due to 75 the contraction of the alcohol or other material inside thereof and the valves will be closed by the action of the spring 22 upon the ends of the levers 15 and 16.

While in the above description we have 80 referred to the use of brine as a cooling medium, it is to be understood that we do not intend to be limited thereby, as our invention is equally capable of use with the so called dry system where air is used for 85 a refrigerant. All that is necessary in the use of air instead of brine is a slightly different type of valve, the principle involved being the same. We therefore intend to claim our invention as adapted for use with 90 any fluid refrigerating or cooling medium.

From the above it will be apparent that we have provided a temperature control which may be easily applied to existing 100 fountains, or the like, where a plurality of compartments are employed and which will efficiently, accurately and automatically control the temperature of the cooling medium in one of said compartments. While we have shown the device applied to one compartment only to control the temperature therein by a cooling medium in an adjoining compartment, it is obvious that the invention may be extended to any number of compartments which may be desired. 105

We are aware that changes in the form, construction and arrangement of parts may be made without departing from the spirit and without sacrificing the advantages of the invention and we reserve the right to 110 make all such changes as fairly fall within the scope of the following claims.

We claim:

1. In a device of the class described, a plurality of compartments, a cooling medium in said compartments, means permitting the circulation of said medium through said compartments, means controlling said circulation and comprising a sylphon, and an auxiliary sylphon associated with said first named sylphon to relieve the pressure thereon when not in use. 120

2. In a device of the class described, a plurality of compartments, a cooling medium in said compartments, means permitting the 125

- circulation of said medium through said compartments, means controlling said circulation and comprising a sylphon, an auxiliary sylphon associated with said first 5 named sylphon to relieve the pressure thereon when not in use, and means for adjusting said auxiliary sylphon.
3. In a device of the class described, a plurality of compartments, a cooling fluid in 10 said compartments, a wall between two of said compartments, a wall between two of said compartments and having a valved opening therein to permit circulation of said fluid, a longitudinally expandible corrugated member for operating said valve, means associated with said member to keep the same 15 from expanding when not in use, and means for controlling the operation of said first named means.
4. In a device of the class described, a plurality of compartments, an insulated wall between two of said compartments, a pair of openings in said wall, a pair of rigid independent levers mounted on said wall, a valve for each of said openings connected to 20 one end of each lever, expandible means co- 25
- operating with the other end of said levers to simultaneously open each of said valves laterally, and a spring oppositely disposed to said expandible means for moving said levers to close both of said valves. 30
5. In a device of the class described, a plurality of compartments, a cooling medium in said compartments, an insulated wall between two of said compartments, openings in said wall for permitting circulation 35 of said cooling medium, non-metallic sleeves in said openings, levers mounted on said wall, a valve for each of said sleeves and connected to one end of each lever, a sylphon for moving each lever to open said valves 40 when said sylphon is expanded, means opposing said sylphon for moving said levers to close said valves when said sylphon is contracted, means associated with said sylphon for relieving the pressure thereon when 45 not in use, and means for adjusting said last named means.

CHARLES L. BASTIAN.
RALPH L. FARNHAM.
